DEVICE FOR AXIALLY SHIFTING CIGARETTES AND MOUTHPIECES TOGETHER

Karl Brunswig, deceased, late of Hamburg-Lohbrugge; by Irma Brunswig, geb. Schmalfeldt, Hannelore Glissmann, geb. Brunswig, and Karin Brunswig, heirs, Hamburg-Lohbrugge, Germany, assignors to Kurt Körber & Co. K. G., Hamburg-Bergedorf, Germany

Application April 23, 1956, Serial No. 593,005

Claims priority, application Germany April 29, 1955

9 Claims. (Cl. 131—94)

This invention relates to shifting devices for cigarettes in general, and more particularly, to shifting devices which effect axial endwise movement of cigarettes into end-to-end engagement. The invention has particular applicability to the axial shifting of cigarettes and mouthpiece attachments therefor, such as filter tips, in conveying apparatus for such cigarettes.

A general object of the invention is to provide an improved axial shifting device for groups of cigarettes and interposed mouthpiece attachments, which will effect end-to-end engagement of such cigarettes and mouthpiece attachments, the latter being initially in a somewhat spaced end-to-end relation.

A more specific object of the invention is to provide an improved shifting device for cigarettes, which are conveyed in the grooves of a conveyor drum, whereby the cigarettes are pressed endwise axially together while in the grooves of the conveyor drum.

A further object of the invention is to provide an improved shifting device, particularly adaptable for high speed operation, in which a pair of spaced disc rings are rotated with a grooved conveyor drum carrying cigarettes within the grooves, the disc rings being resiliently supported by elastic means, such as tension springs, for example, extending radially from the axis of the conveyor drum. The inner ends of the tension springs are preferably secured to a flange ring, secured to and movable with the rotating conveyor drum.

In United States patent application, Serial No. 396,824, and filed December 8, 1953, there is shown and described a device adaptable for shifting together a group of cigarettes and their associated mouthpiece attachments, for instance filter tips, and filter units. The groups of cigarettes are disposed in the grooves of a grooved conveyor drum. The shifting together of the groups of cigarettes must be performed during the continuous movement of the conveying means, for example the grooved conveyor drum, by means of disc rings disposed on the sides of the conveyor drum. The disc rings are biased outwardly in opposite directions, along the axis of the conveyor drum, by helical springs, and the disc rings are engaged by rollers spaced an adjustable distance apart. The helical springs are mounted upon bolts provided with heads, the bolts being positioned concentrically of the axis of the conveyor drum on both sides of the drum.

It was found, however, that when the speed of the drum was increased, the disc rings did not separate quickly enough following their engagement with the guiding rollers. This is believed to result from the friction between the mounting holes in the disc rings and the bolts, which pass through the holes. As a result, the required intermediate space between the disc rings on the opposite side of the drum from the guiding rollers was not always assured.

The present invention eliminates the disadvantages of the foregoing arrangement by biasing the disc rings toward the axis of the conveyor drum by means which ex-

2

tend radially from the axis, and which means are fastened to the ends of the drum. Consequently, the guiding bolts used in the aforesaid application for guiding the springs are rendered unnecessary.

5 A further advantage, according to the present invention, consists in that practically the whole radius of the conveyor drum is available for the length of the spring means employed, so that even despite the rather high speed utilized, and the relatively light spring action, still 10 there is sufficient spring reaction since the extension of the spring means is only a small proportion of its length.

A preferred modification of the present invention provides that the guiding plates comprise two disc rings disposed in the same plane and concentric to the axis of 15 the conveyor drum. The inner ring is flange-shaped in cross-section and is secured to the side of the conveyor drum, whereas the outer of said rings is connected with the flange ring only by elastic means. In order to be able to adjust the distance separating the guiding plates 20 to accommodate different lengths of cigarette groups, there is provided, according to the present invention, means for adjusting axially the guiding plates and their elastic means relative to the sides of the conveyor drum.

Further objects and advantages will readily become apparent upon reading the following specification, taken in conjunction with the drawing, in which:

Fig. 1 shows a vertical sectional view through a preferred embodiment of the invention, illustrating the location of the disc rings with their associated flange rings 30 and the guiding rollers;

Fig. 2 shows fragmentarily an end elevational view of a disc ring and its associated flange ring with tensioning elements, looking in the direction II—II of Fig. 1;

Fig. 3 shows an enlarged cross-sectional view through 35 a disc ring cut with a bevel "a," and in dotted lines its actual engagement with the end of a cigarette group; and

Fig. 4 illustrates a view similar to Fig. 3, but employing 40 an elastic diaphragm, instead of tension springs.

Referring to the drawing, and more particularly to Fig. 41 thereof, the reference numeral 1 designates a shaft mounted in a machine support 2 and carrying a conveyor drum 3 having grooves 4 spaced along its circumference. The conveyor drum 3 may be driven by any suitable means, not shown. In the grooves 4 are disposed, for instance, two cigarettes 5, with a mouthpiece attachment 6 interposed therebetween. The mouthpiece attachment 6, for example, may be a filter tip of double normal length.

On the opposite sides of the conveyor drum 3 are provided 50 a pair of spaced disc rings 7, 8, which are disposed concentrically with respect to the conveyor drum 3. The disc rings 7, 8 are supported by elastic means 9, in this particular instance comprising a plurality of tension spring elements 10. The inner ends of the tension springs 55 10 are connected to flange rings 7a, 8a, associated respectively with the disc rings 7, 8. The flange rings 7a, 8a, are adjustably secured to relatively large flange rings 11, 12 so that they may be adjusted axially along the direction of the shaft 1.

60 As shown in Fig. 1, abutment means, in this instance comprising a pair of spaced abutments 14, having rotatable guide rollers 15 which rotate with respect to the abutments 14, are provided bearing upon the sides of the disc rings 7, 8. In the absence of the abutment means 65 13 with the guide rollers 15, the disc rings 7, 8 would be freely supported upon the flange rings 7a, 8a and would be disposed parallel to the opposite side faces of the conveyor drum 3. The guiding rollers 15, which are 70 rotatably mounted on the abutments 14, bear against the sides of the disc rings 7, 8, at a point on the circumference of the conveyor drum which is nearest to the loca-

tion, at which the cigarette groups 17 are transferred from the conveyor drum 3.

On the opposite side of the conveyor drum, the disc rings 7, 8 being remotely positioned from the rollers 15, are spaced apart a sufficiently large distance to accommodate the insertion of new cigarette groups 17, comprising two cigarettes 5 and the interposed double-length filter tip 6, within the grooves 4 of the conveyor drum 3.

In order to insure that the whole side surface of the disc ring 8, for example, engages the end of the cigarette 5, means are provided to render the side surface of the disc ring 8 parallel with the end surface of the cigarette 5. Fig. 3 shows how this may be accomplished, by providing a bevel 18 on the disc ring 8, having an angle "α" with the vertical.

With reference to the elastic means 9 comprising the tension elements 10, it is obvious that instead of employing tension springs 10, other elastic means could be utilized, such as plate springs, rubber spokes, or the like. It is also possible to use rubber discs, or diaphragms 19, as shown in Fig. 4, secured by screws 20 to the side of a slightly modified disc ring 21. All such elastic arrangements are within the scope of the present invention.

From the foregoing description it is obvious how the arrangement functions, but briefly, by way of recapitulation, the cigarette groupings 17 are carried around by the rotation of the conveyor drum 3. Near the location of the abutment means 13, the disc rings 7, 8 are pressed inwardly by the rotatable guide rollers 15, and this causes the sides of the disc rings 7, 8 to contact the ends of the cigarette groups 17 and to cause a shifting inward movement of the originally spaced cigarettes 5 and the interposed mouthpiece attachment 6. Close end-to-end contact of the cigarettes 5 and mouthpiece attachment 6 results, prior to the transfer of the group 17 off of the conveyor drum 3.

Although there has been shown and described a specific structure of an axial shifting device for cigarettes, it is to be understood that the same has been described merely for the purpose of illustration, and that changes and modifications may readily be made therein by those skilled in the art, without departing from the spirit and scope of the invention.

What I claim as my invention is:

1. A shifting device for axially shifting together a plurality of cigarettes and respective mouthpiece attachments disposed in spaced end-to-end relation including a conveyor drum having a plurality of spaced circumferentially disposed grooves for conveying said cigarettes and mouthpiece attachments in spaced end-to-end relation, a pair of spaced disc rings, elastic means disposed radially of the axis of said conveyor drum for elastically supporting said disc rings radially of the axis of said conveyor drum, and spaced abutment means for bearing upon the disc rings and forcing said disc rings toward each other to shift said cigarettes and mouthpiece attachments together.

2. A shifting device for axially shifting together a plurality of cigarettes and respective mouthpiece attachments disposed in spaced end-to-end relation including a conveyor drum having a plurality of spaced circumferentially disposed grooves for conveying said cigarettes and mouthpiece attachments in spaced end-to-end relation, a pair of spaced disc rings, a pair of associated supporting flange rings, means securing said pair of supporting flange rings to the ends of said conveyor drum concentrically of the axis of said drum, and elastic means extending radially of each supporting flange ring for supporting radially one of said disc rings associated therewith, and spaced abutment means for bearing upon the disc rings and forcing said disc rings toward each other to shift said cigarettes and mouthpiece attachments together.

3. A shifting device for axially shifting together a plurality of cigarettes and respective mouthpiece attachments disposed in spaced end-to-end relation including a conveyor drum having a plurality of spaced circumferen-

tially disposed grooves for conveying said cigarettes and mouthpiece attachments in spaced end-to-end relation, a pair of spaced disc rings, elastic means disposed radially of the axis of said conveyor drum for elastically supporting said disc rings radially of the axis of said conveyor drum, means for axially adjusting said elastic means along the axis of said conveyor drum, and spaced abutment means for bearing upon the disc rings and forcing said disc rings toward each other to shift said cigarettes and mouthpiece attachments together.

4. A shifting device for axially shifting together a plurality of cigarettes and respective mouthpiece attachments disposed in spaced end-to-end relation including a conveyor drum having a plurality of spaced circumferentially disposed grooves for conveying said cigarettes and mouthpiece attachments in spaced end-to-end relation, a pair of spaced disc rings, a pair of associated supporting flange rings, each supporting flange ring and its associated disc ring being disposed in substantially the same plane, means securing said pair of supporting flange rings to the ends of said conveyor drum concentrically of the axis of said drum, and elastic means extending radially of each supporting flange ring for supporting radially one of said disc rings associated therewith, means for axially adjusting said elastic means along the axis of said conveyor drum, and spaced abutment means for bearing upon the disc rings and forcing said disc rings toward each other to shift said cigarettes and mouthpiece attachments together.

5. A shifting device for axially shifting together a plurality of cigarettes and respective mouthpiece attachments disposed in spaced end-to-end relation including a conveyor drum having a plurality of spaced circumferentially disposed grooves for conveying said cigarettes and mouthpiece attachments in spaced end-to-end relation, a pair of spaced disc rings, a pair of associated inner supporting flange rings, each supporting flange ring and its associated disc ring being disposed in substantially the same plane, means securing said pair of supporting flange rings to the end faces of said conveyor drum concentrically of the axis of said drum, and elastic means extending from the inner peripheries of said outer disc rings to the peripheries of said inner supporting flange rings for elastically supporting said disc rings radially of the axis of said drum, and a pair of spaced abutments for bearing upon the disc rings and forcing said disc rings toward each other to shift said cigarettes and mouthpiece attachments together.

6. A shifting device for axially shifting together a plurality of cigarettes and respective mouthpiece attachments disposed in spaced end-to-end relation including a conveyor drum having a plurality of spaced circumferentially disposed grooves for conveying said cigarettes and mouthpiece attachments in spaced end-to-end relation, a pair of spaced disc rings, a pair of associated supporting flange rings secured to the ends of said conveyor drum concentrically of the axis of said drum, a second pair of flange rings supported upon the aforesaid supporting flange rings, means for adjusting the position of said second pair of flange rings axially with respect to said supporting flange rings, and elastic means extending radially of the axis of said conveyor drum from the peripheries of said second pair of flange rings to the inner peripheries of said disc rings to elastically support the same, and a pair of spaced abutments bearing upon the disc rings and forcing said disc rings toward each other to shift said cigarettes and mouthpiece attachments together.

7. A shifting device for axially shifting together a plurality of cigarettes and respective mouthpiece attachments disposed in spaced end-to-end relation including a conveyor drum having a plurality of spaced circumferentially disposed grooves for conveying said cigarettes and mouthpiece attachments in spaced end-to-end relation, a pair of spaced disc rings, elastic means including a plurality of spaced radially disposed elastic elements dis-

posed radially of the axis of said conveyor drum for elastically supporting said disc rings radially of the axis of said conveyor drum, and spaced abutment means for bearing upon the disc rings and forcing said disc rings toward each other to shift said cigarettes and mouthpiece attachments together.

8. A shifting device for axially shifting together a plurality of cigarettes and respective mouthpiece attachments disposed in spaced end-to-end relation including a conveyor drum having a plurality of spaced circumferentially disposed grooves for conveying said cigarettes and mouthpiece attachments in spaced end-to-end relation, a pair of spaced disc rings, elastic means including an elastic diaphragm disposed radially of the axis of said conveyor drum for elastically supporting said disc rings radially of the axis of said conveyor drum, and spaced abutment means for bearing upon the disc rings and forcing said disc rings toward each other to shift said cigarettes and mouthpiece attachments together.

9. A shifting device for axially shifting together a 20

plurality of cigarettes and respective mouthpiece attachments disposed in spaced end-to-end relation including a conveyor drum having a plurality of spaced circumferentially disposed grooves for conveying said cigarettes and mouthpiece attachments in spaced end-to-end relation, a pair of spaced disc rings, elastic means disposed radially of the axis of said conveyor drum for elastically supporting said disc rings radially of the axis of said conveyor drum, spaced abutment means for bearing upon the disc rings and forcing said disc rings toward each other to shift said cigarettes and mouthpiece attachments together, and a side face of at least one disc ring being bevelled so as to be parallel to the end face of one of said cigarettes in the thrust position of said disc ring.
